CLAIM

The ornamental design for a public communication terminal, as shown and described.

DESCRIPTION

FIG. 1 is a front, right side perspective view of a public communication terminal showing our new design;

FIG. 2 is a top plan view;

FIGS. 3 and 4 are respectively rear and front elevational views thereof; and,

FIGS. 5 and 6 are respectively right and left side elevational views thereof.

*Fig. 1.**Fig. 2.*

Fig. 3.
